UNITED STATES PATENT OFFICE.

JOHN B. FREYSINGER, OF STAMFORD, CONNECTICUT, ASSIGNOR TO THE YALE & TOWNE MANUFACTURING COMPANY, OF STAMFORD, CONNECTICUT.

FACING RING FOR CYLINDER LOCKS.

Application filed October 10, 1922. Serial No. 593,489.

To all whom it may concern:

Be it known that I, JOHN B. FREYSINGER, a citizen of the United States, and a resident of Stamford, in the county of Fairfield and 5 State of Connecticut, have invented certain new and useful Improvements in Facing Rings for Cylinder Locks; and I do hereby declare the following to be a full, clear, and exact description of the invention, such as 10 will enable others skilled in the art to which it appertains to make and use the same.

This invention relates to improvements in facing or rose rings for cylinder locks and more particularly to such as receive the 15 flanged or headed end of the lock cylinder.

One object of the present invention is to so construct a facing or rose ring principally of a single piece of sheet metal or hardened steel that it will be difficult or impossible to turn the cylinder in the door 20 because of the fact that the cylinder head is recessed in the ring and thus protected against such attacks, and that the beveled face of the ring will offer no hold for a 25 wrench, aside from the fact that the ring may be provided with a part or parts which enter a notched portion of the door to hold it against any turning movement.

With this and other objects in view, the 30 invention consists in certain novel features of construction and combinations of parts as hereinafter set forth and pointed out in the claims.

In the accompanying drawings—

35 Figure 1 is a view partly in section and partly in elevation illustrating the application of my improvements to a door.

Figure 2 is a front view of the ring, and Figure 3 is a rear view of the same.

40 In the drawings 1 represents a fragmentary portion of a door having an opening 2 therein to receive a cylinder lock 3 and the latter is secured by screws 4 with the casing 5 in which the bolt work of the lock 45 is enclosed, and a notch or recess 6 (or two such notches) is made in the door so as to communicate with the opening 2 in the latter, for a purpose hereinafter explained.

50 My improved facing or rose ring is shown at 7 and comprises a single piece of sheet steel or hardened metal which is bent or formed into proper shape by punching and drawing. When the ring shall have been punched and drawn, it will comprise a base portion 8, a beveled peripheral portion 9

and a depressed portion 10, the latter forming an internal shoulder 11. Prongs or fingers 12 project inwardly from the inner edge of the ring and enter the notch 6 (or two such notches in the event that it is thought desirable to provide two notches 6 instead of one) for the purpose of preventing rotation of the ring. The ring may be covered with a thin scalp 13 of a metal different from that of the ring. 60

The recessed portion of the ring receives the flanged or headed end 14 of the cylinder 3 and the shoulder 11 constitutes a seat for said flange or head 14, a portion of the scalp 13 entering between said flange or head and shoulder, and a portion 15 of said scalp may be made to overlie the back of the ring so as to be disposed between the latter and the outer face of the door 1. 65

70 My improved facing or rose ring may be quickly and cheaply made and it provides, within itself, a re-inforced ring which is so formed in a single piece of sheet metal or hardened steel that it will be difficult or impossible to turn the cylinder in the door, not only by reason of its engagement with the door through the medium of a projection or projections, but also because of the 75 fact that the cylinder head is recessed in the ring and the beveled portion of the ring 80 offers no hold for a wrench. 85

Having fully described my invention what I claim as new and desire to secure by Letters Patent, is:

1. A facing ring for a cylinder lock 90 formed in a single piece of hard sheet metal bent upon itself and providing at its inner edge portion a recessed seat for the flanged or headed end of a cylinder lock.

2. A facing ring for a cylinder lock comprising a single piece of hard sheet metal bent upon itself formed at its inner edge portion with a recessed seat for the flanged or headed end of a cylinder lock, and having a beveled peripheral portion. 95

3. A facing ring for a cylinder lock made in a single piece of hardened sheet metal bent upon itself and formed at its inner edge portion with a recessed seat for the flanged or headed end of a cylinder lock, 105 and a thin scalp of a different metal covering said sheet metal hardened ring.

4. A facing ring for a cylinder lock comprising a single piece of sheet metal bent upon itself and provided at its inner edge 110

portion with a recessed seat for the flanged or headed end of a cylinder lock, said ring provided interiorly with a projection disposed approximately at right angles to the rear face of the ring and having a part to enter a recess in a door adjacent to the opening in the door which receives the cylinder lock.

In testimony whereof, I have signed this specification in the presence of two subscribing witnesses.

JOHN B. FREYSINGER.
Witnesses:

STANLEY C. WHITNEY,
THOS. F. RICHARDSON.
